[57] CLAIM

The ornamental design for a selective call receiver carrier, as shown and described.

DESCRIPTION

FIG. 1 is a top plan view of a selective call receiver carrier showing our design;

FIG. 2 is a front elevational view thereof;

FIG. 3 is a rear elevational view thereof;

FIG. 4 is a bottom plan view thereof;

FIG. 5 is a left side elevational view thereof;

FIG. 6 is a top, front and left side perspective view thereof;

FIG. 7 is a top plan view of a selective call receiver carrier showing a second embodiment of our new design;

FIG. 8 is a front elevational view thereof;

FIG. 9 is a rear elevational view thereof;

FIG. 10 is a bottom plan view thereof;

FIG. 11 is a left side elevational view thereof; and,

FIG. 12 is a top, front and left side perspective view thereof.

The broken line showing of a clip in FIGS. 1-12 is for illustrative purposes only and forms no part of the claimed design.
